DIRECTION-INDICATOR FOR VEHICLES.

1,170,954.

Specification of Letters Patent. Patented Feb. 8, 1916.

Application filed May 13, 1915. Serial No. 27,845.

To all whom it may concern:

Be it known that we, HERMAN H. BROYER, GEORGE CAMBEILH, and JOSEPH PAPALE, citizens of the United States, residing at San Francisco, in the county of San Francisco and State of California, have invented new and useful Improvements in Direction-Indicators for Vehicles, of which the following is a specification.

10 The object of the present invention is to provide a simple, easily operated and effective device whereby the driver of a vehicle can indicate to those in front or behind, either in the day time or at night, the direction in which he intends to drive the vehicle.

In the accompanying drawing, Figure 1 is a perspective view of an automobile equipped with our invention; Fig. 2 is a sectional view of a motor casing looking from the front; Fig. 3 is a similar view looking from the rear; Fig. 4 is a diagrammatic view of the electrical connections; Fig. 5 is a broken sectional view of an arm; Fig. 6 is a broken side view of the end of said arm; Fig. 7 is a side view of a yoke; Fig. 8 is a sectional view of a reflector.

Referring to the drawing, 1 indicates the wind shield of an automobile. On each side 20 of the frame 2 of said wind shield are clamped the side members 3 of a yoke 4, to which is pivotally connected, by a shaft 6 passing through holes in said yoke, an outer yoke 7, the central portion of which is secured to a cylindrical motor casing 8. Springs 9, 10 are secured at their inner ends to a central collar 12 on said shaft and at their outer ends to the side members of the yoke 4, these springs tending to 40 turn the yoke 7 in opposite directions with respect to the yoke 4, and therefore both springs, acting together, to maintain the yoke 7 in a central position. The purpose of this arrangement is so that if the arm 45 hereinafter described, carried with said casing 8, when extending in a horizontal position therefrom, is struck or strikes some object, it will not thereby be injured, but will be permitted to swing about the vertical shaft 6, and afterward will be brought back to its central position relatively to said shaft. The front side of said cylindrical casing is closed by a cover 13, the center of which is apertured, and from which, 55 around said aperture, extends a conical

outwardly flaring reflector 14, having a lens 15, closing the front end of said reflector. In said conical reflector is an electric lamp 16 supplied with electricity by wires 17 leading through said aperture. Said cover 60 has also therethrough an eccentric round hole 18, through which extends rearwardly a round hub or boss 19 of insulating material on the lower end of an arm 21, the front face of which is secured by screws to 65 a wearing plate 22. Said boss is centrally apertured to permit the passage therethrough of a shaft 23, adapted to be rotated as hereinafter described, which shaft has a square end 24 adapted to enter a 70 square hole in the arm 21, and a threaded recess 25 to receive a screw 26 screwed thereto and having a square head 27 which bears against the face of said plate 22. Said arm 21 normally extends in a vertical 75 position and is painted a conspicuous color, as red, and, by means to be presently described, when the driver of the automobile or other vehicle intends to turn to the right or to the left, he causes the arm 21 on the 80 right-hand side or on the left-hand side, as the case may be, to swing into a horizontal outwardly extending position, thus communicating his intentions to those approaching him either from the front or 85 from behind. The outer end of the arm is formed with a round hole in which is secured a cylindrical casing 28 in which casing is an electric lamp 29 supplied with electricity by wires 31 and in the ends of 90 said casing are red or other colored lenses 32. Said wires 31 are electrically connected to conducting plates, one 33 near the center, and the other 34 on the circumference of the boss 19 of insulating material. The 95 conducting plate 33 is in contact at all times with the shaft 23, while the conducting plate 34 is adapted to contact, in a certain position of said shaft, with a spring contact 36. Two of these spring contacts, on opposite sides of the shaft, are shown, so as to 100 enable either arm to be used on either side of the vehicle. When the arm is in an upright position, the conducting plate 34 is not in contact with the spring contact 36, but 105 is brought into contact therewith when the arm is turned to a horizontally outwardly extending position. In said cylindrical casing is an electric motor 38, the shaft 110 of which is operatively connected with the

shaft 23 by a reducing speed gearing 39. To said shaft 23 is rigidly secured a fork 41, between the prongs of which fork is a stud 42 on an arm 43 loosely mounted on the shaft 23. Said stud 42 is connected to one end of a coiled spring 46, the other end of which is connected to a stationary stud 47, said spring, in its central position, passing over the pivotal center 40 of a switch 44 of insulating material. Said switch is in the form of a flat, circular segment and on the opposite margins thereof are secured pairs of contacts 48. These contacts are each adapted to close the circuits between pairs of spring contacts 51. The circuits through the contacts 51, and through the armature and field of the motor are so arranged, as clearly shown in Fig. 4, that, when the switch closes the circuits on one side, the motor rotates in one direction, and when it closes those on the other side it rotates in the opposite direction. Said circuits are also connected, as shown in said figure, with contacts 53, 54, of a three-way switch 56, suitably located, as on the steering handle of the automobile. A fork 57 is secured on an extension of said arm and either tine of said fork is adapted to engage a stud 58 on said switch.

30 The following is the mode of operation of the device. Supposing that the automobile has been traveling straight ahead, then the arm 21 is vertical, and, if at night time, the lamp 16 is lighted, while the circuit through the lamp 29 is broken, owing to the conducting plate 31 on the periphery of the boss 19 being out of contact with the spring contact 36. The switch 44 is on the side to which it has been last shifted, closing the circuits through the pairs of spring contacts 51 on that side. If the operator wishes to turn to the right, for instance, he actuates the switch 56 corresponding to the motor on the right, and thereby completely 45 closes the circuit, which was partly closed by the spring contacts 51. The motor is then energized, and its shaft rotates, causing the fork 41 also to rotate and abut against the stud 42 and then causing the stud 42 to revolve with said shaft about the center of the switch. The spring 46 resists this revolution, but when the stud 42 has passed the pivot of the switch 44, the spring 46 assists 50 the movement of the stud 42, and thereupon

55 the switch 44 immediately moves so as to break the circuits through the spring contacts 51 on the left and to close the circuits through the spring contacts 51 on the right. The spring 46 now completes the rotary 60 movement of the shaft 23 which continues until the arm 21 has moved into a horizontal outwardly extending position, in which position, as already explained, the circuit is closed through the lamp 29. When the operator wishes to go straight ahead again, he operates the three-way switch 56 in the other direction, and the arm 21 moves to a vertical position and the circuit through the lamp 29 is again broken. It is to be understood 65 that it is not absolutely necessary that the lamp at the pivotal axis of the arm should be electric, but it may also be a gas or an oil lamp.

70

75 We claim:

1. In a direction indicating device for vehicles, the combination of an arm pivoted to swing about a horizontal longitudinal axis, a lamp located at the pivotal point of said arm, an electric lamp carried by the end of said arm, means for turning said arm from a vertical to a horizontal position, and means whereby the circuit through the latter lamp is automatically closed when the arm assumes a horizontal position and is automatically opened when it assumes a vertical position.

2. In a direction indicating device for vehicles, the combination of an arm pivoted to swing about a horizontal longitudinal axis, a lamp located at the pivotal point of said arm, an electric lamp carried by the end of said arm, said lamp being unobstructed both at the front and at the rear, means for turning said arm from a vertical to a horizontal position, and means whereby the circuit through the latter lamp is automatically closed when the arm assumes a horizontal position and is automatically opened when it assumes a vertical position.
